VANITY CASE

Ralph C. Bangs, Providence, R. I., assignor to
Juliette G. Wolff, New York, N. Y.

Application October 6, 1932, Serial No. 636,444

9 Claims. (Cl. 132—82)

This invention relates to vanity cases adapted to be carried in the pocket or a handbag and particularly to a type of case for containing loose face powder and supplying it to a powder-puff enclosed in the case.

A particular object of the invention is to provide a vanity case of the type specified having a compartment for the powder-puff, a separate compartment for the powder and means for 10 transferring the powder therefrom to the puff compartment in small quantities as required.

Another object of the invention is to provide a case of the type specified which is adapted to be conveniently filled with the powder and proof 15 against leakage or spillage of the powder therefrom.

Another object of the invention is to provide in a case of the type specified an improved hinge-mounting for the pivoted cover which 20 makes for greater strength and rigidity and insures against loosening and displacement of the parts.

Another object of the invention is to provide a case of the type specified adapted for economical 25 manufacture from sheet-metal stampings and easy assembly of the parts.

Further objects of the invention are set forth in the following specification which describes a preferred form of construction of the case, by 30 way of example, as illustrated by the accompanying drawing. In the drawing:

Fig. 1 is a perspective view of the improved vanity case shown with its cover in open position to disclose the interior;

Fig. 2 is a plan view of the case, also shown with the cover open;

Fig. 3 is a vertical sectional view taken through the median plane of the case with its cover shown in closed relationship;

Fig. 4 is a similar vertical sectional view showing the cover in open position;

Fig. 5 is an elevational view of the case shown in part section and illustrating the manner of assembling the parts thereof; and

Fig. 6 is a similar view showing the cover and base completely assembled.

The present improved vanity case comprises, in its preferred form, a receptacle or bowl 2 for holding a powder-puff; a cover or closure member 3 hingedly connected to the bowl to adapt it to be closed into overlying relationship thereon; and a pliable bag or pouch 4 suspended below the bottom of the bowl for holding the powder.

A hinged lid is provided for closing an opening 55 in the bottom of the bowl through which the

powder may be inserted into the pouch. Small perforations in the bottom of the bowl permit the powder to permeate therethrough from the pouch to impregnate the puff therein.

Referring to the drawing, the puff-receptacle or bowl-member 2 may be of circular or other ornamental contour struck up from sheet-metal with its upper marginal rim 6 rolled or spun outwardly and downwardly to form a depending flange 7 as shown in Figs. 5 and 6. The marginal edge of the bowl is first flanged outwardly and then recessed to form a depressed circular seat 8, upon which the outer rim of the cover member 3 rests when in closed position. The raised bead 9 formed by recessing the rim of the bowl at 8 10 surrounds the edge of the cover 3 when the latter is in closed position, whereby to provide a smooth, 15 flush joint between the parts.

A pliable bag or pouch 4 is attached to the under side of the bowl 2 to serve as a container 20 for loose powder. The pouch 4 may be constituted by a circular piece of leather, fabric or other flexible and impervious material attached to the bowl in any suitable manner. As herein shown, the edges of the pouch material are inserted between the down-turned flange 7 and the sides of the bowl 2, see Fig. 6, and the flange then crimped or rolled inwardly as shown in Figs. 3 and 4 to bind the fabric or other material securely to the rim of the bowl. The area of the 25 fabric or other material of the pouch is proportioned to cause it to sag below the bottom of the bowl 2 to form a separate compartment for holding the powder which is placed therein in the manner as later explained.

In the bottom of the bowl 2 is a rectangular aperture or filler-opening 10 which communicates with the interior of the pouch 4. The filler-opening 10 is provided with a closure or lid 11, preferably hinged to its side in the manner as 30 next described. Held in spaced bearing ears 13 formed on one side of the opening 10 is a hinge-pin 12 on which the lid 11 is pivotally supported by means of a hinge-ear 14 positioned between the ears 13. When the lid 11 is in closed position 35 its forward and lateral edges rest against a recessed ledge 15 formed by offsetting the metal at the edges of the opening 10. On the side opposite from its hinge the lid 11 is provided with an integral ear 17 bent or curled around to form 40 a latch adapted to snap under a detent-lip 18 on the side of the opening 10 when the lid is carried down into closed position as shown in Fig. 3. The lid 11 is thus releasably held in closed 45 position and may be opened at will by merely 50

55 in the bottom of the bowl through which the

pressing it upwardly from its under side to free its latch 17 from the detent-lip 18. Small holes or perforations 29 punched through the bottom of the bowl 2 provide for ingress of the powder 5 to its interior from the pouch 4.

The lid or cover member 3 for the case may be circular in outline or of any other suitable contour to correspond to the shape of the bowl 2. As herein shown, the cover is concavo-convex 10 in cross section to provide a crowned top with its peripheral rim rolled or flanged downwardly in a more abrupt curve. At one side of the rim of the cover 3 is a loop or hinge-ear 19 by means of which the cover is hingedly mounted on a wire 21 secured fast to the rim of the bowl 2. Referring to Fig. 5, the wire 21 is passed through the hinge-ear 19 on the cover 3 and its ends are bent at right-angles in the form of a staple. The legs of the staple are passed through holes 20 punched through the upper rim 6 of the bowl 2 and then clinched or bent upwardly against the under side of the rim. Preferably, the upper rim of the bowl 2 is depressed or recessed at 22 to receive the hinge-ear 19 to insure that the cover 25 3 shall lie flat against the seat 8 of the rim when it is closed down thereagainst.

The cover 3 is releasably held in closed position with its peripheral flange seated snugly against the seat 8 by means of a spring latch or 30 finger 23. The latch 23 projects radially from the outer edge of the cover 3 and is adapted to snap over the rim of the bowl 2 in the manner as illustrated in Fig. 3. The bead 9 on the rim of the bowl 2 is flattened at 24, see Figs. 2 35 and 3, where the latch 23 overlaps the top of the rim. The cover 3 is usually provided with a mirror 25 cemented or otherwise secured to its interior and its exterior may be suitably ornamented or embellished by embossing or engraving 40 designs thereon and by colored enamels when desired.

The present improved vanity case is operated in use in the manner as next explained. To fill the 45 lower pouch 4 the cover 3 is opened as shown in Figs. 1, 2 and 4 and the powder P poured into the bowl 2. The small lid 11 is then opened by pressing upwardly against the bottom of the pouch to disengage the loop 17 on the lid from the detent-lip 18 on the side of the filler-opening 10. The 50 powder can then be fed through the opening 10 into the pouch 4 by tilting and shaking the bowl 2. When the pouch has been filled in the manner as above explained the lid 11 is closed and fastened by the detent-lip 18, see Fig. 3. A 55 powder-puff or chamois p, indicated by dash lines in Fig. 3, is placed in the bowl 2 and the cover 3 closed down until its latch 23 snaps over the rim 8 of the bowl. The vanity case is then ready for use.

60 When it is desired to use the powder the case is held in the hand and by pressing lightly against the pouch 4 with the finger in the manner indicated in Fig. 3 the powder P is pressed against the under side of the bowl 2 and forced through the small perforations 20 to supply the puff p. Only a modicum of powder is transferred to the main compartment of the case to lightly impregnate the puff so that waste and the danger of spillage is avoided. The cover 3 is raised by 65 prying its latch 23 away from the rim of the bowl 2 with the fingernail and lifting it upwardly. With the cover open the puff p may be removed, used, and replaced in the main compartment or bowl 2. When the puff has been replaced in the bowl 2 the cover 3 is again closed 70

75 down upon its seat 8 and its latch 23 snapped over the rim of the bowl to hold it in closed position. The downturned peripheral rim of the cover 3 seats firmly against the seat 8 on the rim of the bowl to form a tight joint which prevents leakage of the powder from the main compartment. 5

It will be observed from the foregoing that the present invention provides a particularly simple and efficient device for the purposes intended. The metal parts of the case are adapted for economical manufacture from sheet-metal stampings and for convenient assembly. 10

A feature of improvement of the present invention consists in providing a vanity case for containing the powder stored in a separate compartment from the puff to avoid the danger of spillage and waste. The powder is thus kept in a clean and dry condition and may be conveniently supplied to the puff in small quantities as required without wasteful excess. 20

The improved method of hinging the cover and bowl together may be applied to other types of cases or containers as providing for greater strength and rigidity with the members less liable to become separated or displaced. 25

While the invention is herein described and illustrated as embodied in a preferred form of construction, it is to be understood that various modifications may be made in the structure and arrangement of the parts of the device without departing from the spirit or scope of the invention. Therefore, without limiting myself in this respect, I claim:

1. In a vanity case, the combination of a concave receptacle having perforations in its bottom, 35 a pouch for powder enclosing the bottom of the receptacle, a filler-opening in the bottom of the receptacle communicating with the interior of the pouch, and means for closing the filler-opening. 40

2. In a vanity case, the combination of a concave bowl having a perforated bottom, a cover therefor, a flexible pouch suspended across the bottom of the bowl for holding a supply of powder, an opening in the bottom of the bowl communicating with the interior of the pouch, closure-means for the opening comprising a lid hingedly connected to the bowl, and detent-means for normally maintaining the lid in closed position. 50

3. In a vanity case, the combination of a concave bowl, a cover hinged to the bowl to close the open top thereof, a flexible pouch suspended across the bottom of the bowl, an opening in the bottom of the bowl through which powder may be 55 supplied to the pouch, means for closing the opening, and perforations in the bowl through which a modicum of powder may be transferred from the pouch to the interior of the bowl.

4. In a vanity case, the combination of a bowl 60 having its upper rim extended to form a circular seat with a flange depending therefrom, a cover hingedly connected to the bowl to adapt it to close down upon its seat, and a flexible pouch secured to the edge of the bowl by the depending flange and the under side of the rim forming the seat with the entire peripheral edge of the pouch gripped therebetween.

5. In a vanity case, the combination of a bowl 70 having its upper rim extended to form a flat circular seat with an enclosing shoulder and then folded downwardly to provide a depending flange, a cover hingedly connected to the bowl to adapt it to close down upon its seat with its peripheral edge enclosed by the shoulder on its rim, and a 75

flexible pouch secured to the rim of the bowl by the depending flange and the under side of the rim with the entire peripheral edge of the pouch gripped therebetween.

- 5 6. In a vanity case, the combination of a bowl having a flared rim with perforations therein, a cover having a hinge-ear, and means for pivotally connecting the cover to the bowl comprising a U-shaped hinge-wire inserted through the hinge-ear with its right angled legs projecting through the perforations and bent over to clinch them against the under side of the rim whereby the hinge wire forms a pivot for the cover on the outer side of the rim.
- 10 7. A container for loose powder comprising a pouch for holding the powder, a closure plate for the mouth of said pouch, said plate having an opening for the passage of powder, an upstanding wall associated with the closure plate and
- 15

forming therewith a chamber for a puff, and a cover hingedly associated with the closure plate.

8. A container for loose powder comprising a pouch for holding the powder, a closure plate having its rim bent upwardly to form a wall defining a chamber for a puff and then bent downwardly to form a lip, the mouth of the pouch being gripped between said lip and said wall, the closure plate having an opening for the passage of the powder, and a cover hingedly associated with the closure plate.

9. A container for loose powder comprising a pouch for holding the powder, a closure plate for the mouth of said pouch, said plate having an opening for the passage of powder, an upstanding wall associated with the closure plate and forming therewith a chamber for a puff, and a cover for said chamber.
